UNITED STATES PATENT OFFICE.

CARL H. ZWERMANN, OF KALAMAZOO, MICHIGAN.

KILN CONSTRUCTION.

1,216,390.

Specification of Letters Patent. Patented Feb. 20, 1917.

Application filed December 4, 1916. Serial No. 134,988.

To all whom it may concern:

Be it known that I, CARL H. ZWERMANN, a citizen of the United States, residing in the city and county of Kalamazoo, State of Michigan, have invented certain new and useful Improvements in Kiln Constructions, of which the following is a specification.

This invention relates to improvements in kiln construction, particularly to improvements in kilns for the firing of pottery and enameled ware.

The objects of the invention are to provide an improved construction of hot air flues and arrangement of the same especially well adapted to use in tunnel kilns; although adaptable to other kilns as well. The invention relates particularly to an arrangement of sectional hot air flue construction and arrangement and disposition of the same in conjunction with the combustion chamber whereby efficient and effective circulation of hot air through the ware being fired is insured.

Objects relating to details and economies of construction and operation will definitely appear from the detailed description to follow.

I accomplish the objects of my invention by the devices and means described in the following specification. The invention is clearly defined and pointed out in the claims.

Structures showing preferred embodiments of my invention are clearly illustrated in the accompanying drawing forming a part of this specification, in which:

Figure I is a transverse detail sectional view through the body of a kiln embodying the features of my invention.

Fig. II is an enlarged detail sectional view of one of the flue sections.

Fig. III is an enlarged detail transverse horizontal sectional view taken on a line corresponding to lines 3—3 of Figs. I and IV.

Fig. IV is an enlarged detail longitudinal sectional view taken on a line corresponding to the irregular line 4—4 of Figs. I and III.

Fig. V is a detail transverse sectional view through the lower part of a tunnel kiln embodying my invention.

In the drawing the sectional views are taken looking in the direction of the little arrows at the ends of the section lines and similar numerals of reference refer to similar parts throughout the several views.

Considering the lettered parts of the

drawing, 1 is the outer wall or shell and 2 the inner wall or lining, usually of fire brick or fire resisting material between which are interposed insulating materials 3. A 60 floor 4 of fire brick or other fire resisting material is supported upon an insulating bed 5.

At the center and beneath each side are series of hot air pipes 6 disposed longitudinally thereof and leading from the outer or mouth end of the kiln through to a transverse air space 7. Into the tail end delivers the flue pipe 8 which is directed into the combustion chamber 9 at each side.

A platform 10 is provided on the floor at the center of the kiln with suitable supporting rails or ribs 11 for carrying the ware or the saggars containing the same. Partial partition walls 12 at each side separate the central platform from combustion chambers 9 at each side, being spaced above the floor and extending to line beneath thereof.

The combustion chambers are contained within flue sections made up of a base flue 13 opening toward the central platform and closed at its outer end. Vertical pipes 14 at the outer end and 15 at the inner end connect to flanged apertures 16 and 17 in the upper side thereof. The flue 13 is U-shaped in cross section disposed flat side down. The vertical tubular flues 14 and 15 connect to and assist in supporting a cap flue chamber 18 which is somewhat A-shaped or arched with flanged apertures 19 and 20 for the upper ends of the tubular flues 14 and 15, respectively, and with a discharge port 21 at the top, delivering upwardly and inwardly at the top of the kiln chamber. Cap member 18 extends outwardly beyond the tube 14 and engages a ledge 19' in the upper portion of the inner side wall 2. The inner portion is extended and engages and rests upon the upper edge of the partition wall 12 whereby this flue cap is supported and rests only lightly upon the vertical tubular flues 14 and 15 so that when these vertical tubular flues become highly heated, as they will from their presence directly in the combustion chamber, there is substantially no weight resting upon them that would tend to distort or collapse them, a matter of high consequence in view of the high temperature to which these parts are subjected.

The flue space 22 is across the combustion chamber at the tail end of the kiln which connects to a chamber flue space 23 under-

neath the combustion chamber at each side, which is connected to an exhaust flue 24 toward the inner end of the kiln, which flue either connects to a chimney or to an exhaust fan to create the necessary draft to insure the proper delivery of the fuel and air within the combustion chamber.

It will be seen from this description that fuel and air enter the combustion chambers and circulate through the same to the flue space at the mouth end of the kiln and are thence carried downwardly and back toward the tail of the kiln underneath the combustion chamber. The air pipes 6 being disposed in this chamber 23 will become greatly heated and deliver heated air into the air flue or space 7 at the tail end of the kiln where the same will come in contact with the fuel and insure, owing to the high temperature, its rapid and complete combustion.

Ware placed in the kiln chamber will be heated by a circulation of the comparatively cool air at the bottom of the kiln, laterally outward into the flues 13, thence upwardly through the flues 14 and 15 out into the top chamber flue 18, thence through the port 21 into the top of the kiln, and thence down over the ware disposed therein.

It will be clear that the air flues herein may be readily renewed when they have been worn or burned out in use. These air flues are spaced from each other and held in spaced relation and alinement at their bases by interlocking lugs 13' and 13'', respectively, (see Fig. III). This permits expansion and contraction without disturbing the relation of the parts.

In Fig. V, I have shown my improved kiln structure adapted to a tunnel kiln, a railway track 25 being provided in the bottom of the kiln on which cars or trucks 26 for the ware are propelled through the kiln. I provide longitudinal sand troughs 27 filled with sand 28 at each side, and downwardly projecting slide guard plates 29 at each side of the car, extend into the sand at their lower edges to shut off the heat from the trucks beneath which otherwise might become heated to an injurious extent.

The operation of the tunnel kiln is the same as the other except that the trucks 26 are pushed or propelled through it.

It is clear that my improved kiln can be considerably modified in detail without departing from my invention.

Having thus described my invention, what I claim as new and desire to secure by Letters Patent is:

1. In a kiln structure, the combination of the outer and inner walls suitably insulated, suitable central supports for the ware with a central kiln chamber therefor, partial partition walls separating the combustion chamber at each side, lateral flues comprising a tubular base portion with flanged aper-

tures on the upper side and with spacing lugs on the lateral sides thereof, upright tubular flues connecting to said base portion disposed in the flanged openings, a flue cap with flanged openings for the upper ends of said upright tubular flues and extending beyond the same, and ledges formed on the inner walls for supporting the flue caps, coacting substantially as described for the purpose specified.

2. In a kiln structure, the combination of the outer and inner walls suitably insulated, suitable central supports for the ware with a central kiln chamber therefor, partial partition walls separating the combustion chamber at each side, lateral flues comprising a tubular base portion with flanged apertures on the upper side, upright tubular flues connecting to said base portion disposed in the flanged openings, and a flue cap with flanged openings for the upper ends of said upright tubular flues, coacting substantially as described for the purpose specified.

3. In a kiln structure, the combination of the outer and inner walls suitably insulated, suitable central supports for the ware with a central kiln chamber therefor, partial partition walls separating the combustion chamber at each side, lateral flues comprising a tubular base portion with spacing lugs on the lateral sides thereof, upright tubular flues connecting to said base portion, and a flue cap with flanged openings for the upper ends of said upright tubular flues, coacting substantially as described for the purpose specified.

4. In a kiln structure, the combination of the outer and inner walls suitably insulated, suitable central supports for the ware with a central kiln chamber therefor, partial partition walls separating the combustion chamber at each side, lateral flues comprising a tubular base portion, upright tubular flues connecting to said base portion, and a flue cap with flanged openings for the upper ends of said upright tubular flues, coacting substantially as described for the purpose specified.

5. In a kiln structure, the combination of the walls suitably insulated, suitable central supports for the ware with a central kiln chamber therefor, partial partition walls separating the combustion chamber at each side, lateral flues comprising a tubular base portion projecting under said partial walls with upright tubular flues connecting to said base portion, a flue cap with flanged openings for the upper ends of said upright tubular flues and extending beyond the same, and internal ledges formed on the walls for supporting the flue caps, coacting as described.

6. In a kiln structure, the combination of the walls suitably insulated, suitable central supports for the ware with a central kiln chamber therefor, lateral flues comprising a

tubular base portion with upright tubular flues connecting to said base portion, a flue cap for the upper ends of said upright tubular flues and extending beyond the same, 5 and internal ledges formed on the walls for supporting the flue caps, coacting as described.

7. In a kiln structure, the combination of the walls suitably insulated, suitable central supports for the ware with a central 10 kiln chamber therefor, lateral flues comprising a tubular base portion with upright

tubular flues connecting to said base portion, and a flue cap for the upper ends of said upright tubular flues, coacting as de- 15 scribed.

In witness whereof I have hereunto set my hand and seal in the presence of two witnesses.

CARL H. ZWERMANN. [L. s.]
